UNITED STATES PATENT OFFICE.

WILLIAM H. SMITH, OF BUFFALO, NEW YORK, ASSIGNOR TO JOHN R. KEIM MILLS, INC.,
OF BUFFALO, NEW YORK, A CORPORATION OF NEW YORK.

APPARATUS FOR MAKING CUP-SHAPED ARTICLES.

No. 908,342.

Specification of Letters Patent.

Patented Jan. 12, 1909.

Application filed May 27, 1907. Serial No. 375,794.

To all whom it may concern:

Be it known that I, WILLIAM H. SMITH, citizen of the United States, residing at Buffalo, in the county of Erie and State of New York, have invented a new and useful Improvement in Apparatus for Making Cup-Shaped Articles, of which the following is a specification.

This invention relates to an apparatus for forming of sheet metal cup-shaped articles of rectangular or irregular contour. By the use of the apparatus heretofore known such articles could only be produced by a succession of operations each of which changed the shape of the article but very little in order to avoid producing wrinkles at the corners of the article which is objectionable. The large number of operations heretofore necessary for producing such articles in this manner rendered the cost of the same unduly high and commercially prohibitive. This difficulty does not arise when drawing down a cylindrical or nearly cylindrical blank inasmuch as the flow of the metal while being drawn is uniform around the entire blank and no tendency therefore exists to wrinkle in any particular place.

It is the purpose of this invention to enable cup shaped articles of rectangular or irregular form to be drawn to a greater extent at each operation without liability of wrinkling the same, thereby reducing the number of steps necessary to bring the article into its final shape and minimizing the expense accordingly.

In the accompanying drawings: Figure 1 is a sectional elevation of my improved drawing apparatus showing the parts in position for reducing a cup-shaped blank. Fig. 2 is a fragmentary top plan view showing the die and the outer blank holder. Fig. 3 is a bottom plan view of the inner blank holder and punch.

Similar letters of reference indicate corresponding parts throughout the several views.

The cup-shaped blank A which is to be operated upon by my improved drawing apparatus is first produced from a flat sheet of metal in the usual manner so that it has the general form of the finished article into which it is to be transformed. The form of the blank after this preliminary operation is shown in Fig. 1.

B, C represent the cooperating die and

punch, respectively, which form part of my improved apparatus whereby the blank is drawn into the desired shape. The die is provided with a central opening b corresponding to the shape which the blank is to receive and on its front side with an angular or beveled gripping face d around the edge of said opening. The punch is of the same dimensions and shape but slightly smaller than that of the opening in the die and may be reciprocated by any suitable means common to this class of machinery. The cup-shaped blank is placed with the marginal beveled part a of its bottom a' on the inclined or angular face d of the die and then pushed through the opening in the die by the punch moving into the blank and engaging with the inner side of its bottom in a well known manner. While thus drawn the blank is supported on its inner side by an inner blank holder E which is similar to those in common use, the same being tubular form and fitting with its outer side against the inner side of the hollow blank while its lower or front beveled end or gripping face e is arranged opposite the inner part of the beveled face of the die so that the marginal part of the blank bottom is clamped between the correspondingly beveled faces d and e of the die and inner blank holder. The pressure of the latter is only sufficient to hold the same in place and permit the blank to be drawn by the punch from the outer side of the inner blank holder inwardly between the beveled faces d, e and thence downwardly through the die, whereby the blank is elongated but reduced in a diameter or girth.

The construction and operation of the parts thus far described are old and well known in the art.

In the absence of any other provision the reduction in diameter or change from one shape of the cup blank to another would have to be effected by comparatively small steps inasmuch as large reducing steps would cause the metal to gather and wrinkle outside of the gripping faces d, e which is objectionable. This wrinkling occurs more particularly at the corners of rectangular or irregularly shaped blanks. To prevent the metal from gathering and wrinkling at the corners of the gripping faces and still permit a comparatively large draw of the blank to be made in one operation, an outer

blank holder is provided. In the construction of the outer blank holder shown in Figs. 1 and 2, the same has the form of a rectangular frame G which fits with its inner side 5 against the outer side of the blank and is provided on its front or underside with a beveled face g which fits the outer part of the beveled face d of the die. The outer holder thus forms an upward extension of 10 the die above the place where the gripping faces d and e of the die and inner blank holder coöperate. This extension together with the opposing part of the inner blank holder forms a guide which controls the 15 movement of the metal in the body or side part of the blank before it makes an inward turn at the angles d, e. The metal in the body of the blank is by this means caused to distribute uniformly, thereby preventing an 20 excess flow toward the corners and avoiding gathering or wrinkling of the metal. In the straight parts of the side of the blank there is little if any tendency of the metal to wrinkle owing to the greater area over which 25 it can distribute itself and it is therefore unnecessary for the outer blank holder to completely inclose the blank, it being sufficient to engage the blank at the corners only where the wrinkling is most liable to occur. 30 By the use of my improved apparatus it is possible to draw rectangular or irregular cup-shaped blanks considerably greater distances during each operation than has been possible heretofore without producing wrinkles, thus enabling the number of operations 35 to complete the drawing to be lessened and rendering the manufacture of such articles in this manner commercially practical.

I claim as my invention:

1. An apparatus for producing articles 40 from cup-shaped blanks, comprising a die having an opening and a beveled face around said opening, a punch adapted to move through said opening, an inner blank holder adapted to engage with the inner side of the 45 body of the blank and having a beveled face at its front end which coöperates with the inner part of the beveled face of the die for clamping the bottom of the blank between the same, and an outer blank holder engag- 50 ing with the outer side of the body of the blank and having a beveled face which fits the outer part of the beveled face of the die, substantially as set forth.

2. An apparatus for producing articles 55 from cup-shaped blanks, comprising a die having an opening and a beveled face around said opening, a punch adapted to move through said opening, an inner tubular blank holder adapted to engage with the inner side 60 of the body of the blank and having a beveled face at its front end which coöperates with the inner part of the beveled face of the die for clamping the bottom of the blank be- 65 tween the same, and an outer frame-shaped blank holder engaging with the outer side of the body of the blank and having a beveled face which fits the outer part of the beveled face of the die, substantially as set forth.

Witness my hand this 20th day of May, 70
1907.

WILLIAM H. SMITH.
